(57) **CLAIM**

The ornamental design for gelato container, as shown and described.

DESCRIPTION

FIG. 1 is a perspective view of a gelato container showing my new design;

FIG. 2 is a top plan view thereof;

FIG. 3 is a side elevational view thereof;

FIG. 4 is a front elevational view thereof; and,

FIG. 5 is a bottom plan view thereof.

The broken line showing of interior contents and indicia are included for the purpose of illustrating environmental structure and forms no part of the claimed design.

1 Claim, 5 Drawing Sheets

FIG. 2

FIG. 3

FIG. 4

FIG. 5
